United States Patent Office.

FLORENTINE A. JONES, OF BOSTON, MASSACHUSETTS.

Design No. 4,459, dated November 8, 1870.

DESIGN FOR A WATCH-PLATE.

The Schedule referred to in these Letters Patent and making part of the same.

I, FLORENTINE A. JONES, of Boston, in the county of Suffolk and State of Massachusetts, have invented and produced a new and original Design for a Watch-Plate, of which the following is a specification.

The drawing represents a plan view of my improved design for watch-plate.

C represents a semicircular plate, suitably attached to the base-plate A.

The plate C is provided with the circular depressions F, which merge into each other, and receive the gearings for the winding mechanism.

Adjoining the depressions F are recesses, in which are located the pawl H and spring I.

By this arrangement a saving of space is effected, as the winding-wheels are flush with the surface of

plate C, while heretofore they have projected above the same. This feature constitutes my design.

Having thus fully described my invention,

What I claim as new, and desire to secure by Letters Patent, is—

The design for watch-plate C, having depressions F, with their adjoining recesses, substantially as described.

In testimony whereof, I have signed my name to this specification in the presence of two subscribing witnesses.

FLORENTINE A. JONES.
